UNITED STATES PATENT OFFICE.

FREEBORN F. RAYMOND, 2D, OF NEWTON, MASSACHUSETTS.

COMB NAIL-STRIP.

SPECIFICATION forming part of Letters Patent No. 467,237, dated January 19, 1892.

Application filed May 15, 1885. Serial No. 165,574. (No model.)

To all whom it may concern:

Be it known that I, FREEBORN F. RAYMOND, 2d, a citizen of the United States, residing at Newton, in the county of Middlesex and State 5 of Massachusetts, have invented a new and useful Improvement in Comb-Strips of Heel-Nails, of which the following is a full, clear, and exact description, reference being had to the accompanying drawings, forming a part 10 of this specification, in explaining its nature.

This invention relates to comb-strips of heel-nails, as will be more fully hereinafter described, and pointed out in the claim.

Figure 1 is an elevation of a comb-strip, 15 showing nails of different lengths. Fig. 2 shows a strip formed to approximate the line or arrangement upon which the nails are driven in attaching the heel. Fig. 3 is an elevation showing a modified form of the construction represented in Fig. 1, the nails being of varying lengths.

a is the comb-strip. It has formed to project from the connecting section or margin a as many nails a' as it is desired to feed to the 25 heel-attaching machine and no more. For instance, if nine nails are needed for properly attaching the heel-blank, then the comb-strip has but nine nails. If fifteen are necessary, then the comb-strip has fifteen, and so on. Of 30 course the strip may have any number necessary for the heel which its nails are to attach.

The nails as supported by the comb are of varying lengths, and this may be also produced by forming the strip as shown in Fig. 35 3, so that the uncut margin describes a curve; or the uncut margin may be straight and the shanks of the nails extend therefrom of varying lengths, as represented in Figs. 1 and 2. The nails also may be of varying size to fit 40 them for the especial location which they are to bear in the heel, as it is desirable that cer-

tain nails for attaching the heel be larger or longer, or both, and possess greater wearing properties than others.

In use the comb-strip having the requisite 45 number of nails and of the requisite size and length is placed in the machine, and by the operation thereof it is separated into its individual nails, which are fed to the driving devices and driven. It is obvious that this strip 50 not only provides means for easy and quick feeding of a large number of nails, but that it also provides means for the feeding of nails of different lengths and sizes in a quick and expeditious way, and also for properly locating 55 such nails so that all the nails are fed to the place where needed, whether they be long, short, stout, or slender.

While I have described this invention as applicable to heel-nails, I would not be understood as limiting it to this class of fastenings, 60 as it may also be used for fastening soles or any other article or thing where it is necessary to feed the nails or fastenings expeditiously, and to arrange for the driving of a 65 given number, and to provide nails or fastenings of varying lengths and sizes adapted to be driven in special or prearranged places.

Having thus fully described my invention, I claim and desire to secure by Letters Patent 70 of the United States—

A comb-strip of heel-nails, composed of a predetermined number of starts increasing in length from the ends of the strip entire toward the center thereof, connected by a top 75 web adapted to be cut to separate the nails or starts for individual driving, substantially as described.

FREEBORN F. RAYMOND, 2D.
